UNITED STATES PATENT OFFICE

133,561

DESIGN FOR A SELF-INDICATING PUSH BAR

Leslie W. Gillette, Chicago, Ill.

Application September 27, 1940, Serial No. 95,442

Term of patent 7 years

To all whom it may concern:

Be it known that I, Leslie W. Gillette, a citizen of the United States and resident of Chicago, in the county of Cook and State of Illinois, have invented a new, original, and ornamental Design for Self-Indicating Push Bar, of which the following is a specification, reference being had to the accompanying drawing, forming part thereof.

Fig. 1 is a perspective view of a push bar showing my new design. The entire bar is intended to be substantially transparent.

Fig. 2 is a top plan view;
Fig. 3 is a front elevational view;
Fig. 4 is a left-hand end view.

The right-hand end view and the bottom of the bar are plain.

I claim:

The ornamental design for a self-indicating push bar, substantially as shown and described.

LESLIE W. GILLETTE.
